DESIGN FOR A DOLL

Kathryn G. Schnell, Toledo, Ohio

Application December 23, 1944, Serial No. 117,060

Term of patent 14 years

(Cl. D34—4)

To all whom it may concern:

Be it known that I, Kathryn G. Schnell, a citizen of the United States and resident of Toledo, in the county of Lucas and State of Ohio, have invented a new, original, and ornamental Design for a Doll, of which the following is a specification, reference being had to the accompanying drawing, forming a part thereof.

In the drawing, Fig. 1 is a front view of a doll, in sitting position, showing my new design; Fig. 2 is a rear view thereof, and Fig. 3 is a side view thereof.

I claim:

The ornamental design for a doll, substantially as shown.

KATHRYN G. SCHNELL.
